UNITED STATES PATENT OFFICE.

GUSTAVE M. NELL, OF DENVER, COLORADO, ASSIGNEE OF ONE-HALF TO ERIC B. HUNGERFORD, OF DENVER, COLORADO.

ADDING-MACHINE.

1,087,135.

Specification of Letters Patent. Patented Feb. 17, 1914.

Application filed November 5, 1912. Serial No. 729,870.

To all whom it may concern:

Be it known that I, GUSTAVE M. NELL, a citizen of the United States, residing at Denver, in the county of Denver and State 5 of Colorado, have invented certain new and useful Improvements in Adding-Machines, of which the following is a specification.

This invention relates to adding machines; and one of its objects is to provide 10 a machine of this character which is simple and compact in construction, reliable and efficient in action, and adapted to be operated with facility.

This invention relates to adding machines; and it has for its primary object the 15 provision of means for facilitating the operation of resetting the number wheels and the construction of said means whereby said wheels will be normally held in an active 20 adding condition.

A further object of the invention is the provision of means for simplifying the operating connections between the keys and main transmitting wheel and for insuring 25 accurate revolving operations of the number wheels as the keys are actuated and for arranging the parts, so that the machine as a whole is relatively compact.

A still further object of the invention is 30 to provide a machine which may also be used in operations requiring multiplication and subtraction.

With these and other objects in view, the invention consists of certain novel features 35 of construction, combination and arrangement of parts, as will be hereinafter described and claimed.

In the accompanying drawings:—Figure 1 is a top plan view of an adding machine 40 embodying my invention; Fig. 2 is a similar view of the intermittently movable carriage and the registering devices mounted thereon; Fig. 3 is a side elevation of the machine; Fig. 4 is a view of the vertically movable transmission frame or rack and parts 45 associated therewith; Fig. 5 is a detail section on the line 5—5 of Fig. 4; Fig. 6 is a vertical front to rear section through the machine; Fig. 7 is a detail vertical transverse section through two adjacent registering wheels and the resetting wheel together 50 with the coating parts; Fig. 8 is a detail section on the line 8—8 of Fig. 7; and Fig. 9 is a diagrammatic elevation of the verti-

cally movable transmission frame or rack 55 and the operating keys, showing their normal relative arrangement.

The casing 1 of the machine has its top wall provided with a view opening 2 through which a carriage 3 of the adding mechanism is adapted to be exhibited, said carriage having longitudinal flanges 4 thereon which are mounted in guides 5 in the casing 1 and adapted to travel horizontally through the slots 6 in the ends of said 65 casing. The carriage supports a normally fixed axle 7, on which the gear wheels 8 of the adding train are mounted and adapted to freely revolve, each of said wheels having secured thereto a band 9 bearing the numerals from "One" to "Zero" and arranged whereby the registered additions may be displayed through the opening 2 of the casing 1 and through the openings 10 of a shield plate 11 of the carriage. Each 75 of said gear wheels 8 is provided with an integral ratchet surface 12, a pivoted pawl 13^a and a spring 14, the latter being yieldingly engaged with the pawl as shown in Fig. 8 of the drawings. The wheels 8 are 80 arranged relatively so that the pawl 13^a of one wheel will be moved into engagement with the ratchet wheel or surface 12 of the preceding gear wheel for a purpose to be hereinafter described. Cams 15 are splined 85 to the axle 7 and disposed between the companion gear wheels 8 and operatively associated with the pawls 13^a whereby to lift the latter from the ratchet surfaces of the wheels and to permit of an engagement of 90 said pawls with the ratchet surfaces of the preceding gear wheels of the train on each complete revolution of the adjacent adding element. This construction is necessary to render the machine accurate when adding 95 in that, and, assuming as an example that one of the elements of the adding train has registered (9.) and it is desired to add (9.) thereto, the transmission will be operated as for the first (9.) to bring the element to a 100 position within one point of the (9.). In other words, the succeeding adjustment of the element brings the "9" indication thereof into registration with the view opening, and in that the element has made a complete revolution, the dog 13^a thereof will be 105 moved into the ratchet of the left preceding recording element so that the same will be

revolved, one point and to indicate with the first element that the added total is (18.).

A clearing or resetting gear wheel 14 is keyed at 15 to the axle 7 and provided with 5 a ratchet surface 16, coöoperating with a cam 12^a which ratchet surface and cam are engaged by the pawl 13 of the adjacent adding gear wheel 8 as illustrated in Fig. 7. At the opposite end, the axle 7 has keyed there- 10 to for longitudinal adjustments a manipulating knob 17 having a locking stud 18 at one side which may be projected into a keeper opening 19 in the head 20 of the adding carriage. A stop washer 21 of the axle 15 has one end of a spring 22 engaged there-against while the opposite end of said spring is seated against the knob 7 whereby the stud 18 of the latter will be properly held in said opening 19 and the axle normally 20 held against rotation. Now, through the fact that the gear wheels 8 are mounted to freely revolve on the axle 7; that they are associated with the cams 13, and the pawls 13^a, as described, and further through the 25 provision of the fixed gear 14, ratchet surface 16, cam 16^a and a manipulating knob 17, it will be evident, that, by first drawing the knob to a released or retracted position, and then turning said knob, to revolve 30 the axle 7 in a counter clockwise direction the ratchet surface of the wheel 14 will be engaged by the pawl 13^a of the right adjacent adding wheel 8 and as the movement of the axle is continued all of the companion 35 pawls of the adding mechanism will be moved, in proper turn, to operate and reverse the direction of motion of the preceding adding wheels, with a resultant restoration of the "Zero" indications of said wheels 40 to their initial positions behind the view openings of the carriage. Yieldable dogs 23 upon the shield 3 of the carriage engage with the wheels 8 whereby to secure regularity of movement and to compensate for 45 wear of the wheels and thereby insure their positive action and encourage proper recording movements of said wheels.

The transmitting mechanism of the machine comprises a transmitting axle 24, which 50 is provided intermediate of its ends with a gear wheel 25 which is normally free to revolve on the axle and which is shown to include an integral ratchet wheel 26, which is adapted to be engaged by a spring 55 pressed dog or pawl 27 pivoted to one side of a wheel 28 fixedly mounted on the axle and provided with a peripheral substantially V-recess 29 to receive one end of a rocking escapement 30. The transmitting 60 axle 24 is provided with fixed end pinions 31, which are arranged in intermeshing engagement with the teeth of vertically-moving rack bars 32 of an actuating frame 33. This frame is mounted in suitable guides 34 65 in the casing 1 and connected with a sus- taining spring 35 of said casing 1 whereby the frame 33 is normally held in an elevated position. The adding keys 36 which are marked from "one" to "zero" are mounted to slide vertically through guide openings 37 in the top of the casing 1 and through similar openings 38 in an extension bracket 39 of said casing. These keys are provided with lower horizontal arms 40 which are terminally located directly above the plane of the pressure bar 41 of the vertically sliding rack frame 33 and at different distances therefrom so that the keys when depressed to their limit, control the relative distances through which the rack is depressed, with a resultant proportionate transmission of motion to the adding wheels. Such construction is common to all of the keys, excepting the "zero" key. This key is terminally provided with spaced lugs 42 between which is extended the long arm 43 of a rocking lever 44 on the axle 24 of the transmitting mechanism.

The escapement dog 30 is pivoted at 45 to the casing 1, and as shown, said escapement is provided with a depending arm 46, which is connected with a spring 47 of the casing, the latter exerting its influence to hold said escapement engaged in the keeper recess 29 in the wheel 28. The lever 44 carries a short arm 48 which is adapted to engage the detent 30 and to move said detent in one direction when the "zero" key is depressed. The keys 36 are normally held in elevated positions through the medium of springs 49 which are secured at 50 to the lower ends of the keys, while at 51, the springs are secured to the extension 39 of the casing 1. Stop projections 52 on the keys are adapted to engage against the top 55 walls of the casing 1 whereby the return movement of each key is limited under the purpose of its spring 49.

The carriage 3 has one of its guide flanges 4 provided with a longitudinal slot 53 whose opposite side walls are provided with teeth 54, the stop shoulders or surfaces 55 of the teeth of one wall being disposed out of the plane of the shoulders 55 of the teeth on the opposite wall of the slot. 60 In other words, the companion rows of teeth are arranged substantially in staggered relation. A spring 56 is connected at one end to the carriage 3 and at its opposite end to one of the end walls of the casing 1, whereby 65 its pressure will be exerted to move the carriage toward the left of the machine. A finger piece 57 of the carriage may be operated by the thumb when it is desired to move the carriage in an opposite direction. The detent 30 carries a projecting carriage locking and releasing finger 58 which extends through the slot 53 where it is adapted under rocking movements of the escapement 70 to successively engage the companion teeth 75

55 and thereby permit the carriage to move intermittently.

A pointer 39 of the casting 1 extends into the opening 2 of the casing where it is disposed directly over the shield 3 where it may be made to register with any one of the adding wheels. A fixed stop 60 rises from the shield of the carriage and is adapted to coöperate with pivotally adjustable stops 61, 62 and 63 on the casing 1. Each of the stops 61, 62 and 63 bear an indicating mark or number 64 so that each adjustable stop when adjusted to coöperate with the fixed stop 60 will retain adjustments of the carriage when adding items that fall within a certain range. A spring dog 65 is associated with transmitting gear wheel 25, whereby to hold the latter against retrograde rotation while the frame 33 is returning to its normal position after having been depressed.

The keys 36, as stated are adapted to operate said rack frame 33 on their downward movements thereby operating the cog wheels 31 and in turn the transmitting gear 25 and then the particular gear wheel of the adding train as may depend on the position of the carriage.

Now that the details of construction of the machine are clearly disclosed a brief illustration as to the mode of operation is given in the following and it will be supposed that the numbers indicated below are to be added:

35	120.00
	98.00
	3.05
	.01
	1,000.00

40 Depress the "zero" key a sufficient number of times to bring the carriage to the left and to such position as will cause the stop 60 to pass the coöperating "100" stop. The carriage is then moved to the right until the stop 60 positively engages said "100" stop, and then for the item "120.00" depress key "1", followed by key "2". The carriage is then drawn to its normal 100.00 position and for 98.00 the "zero" key is depressed once to bring the carriage to the tens of dollars column; then key 9, followed by 8. Return carriage to normal position, which is 100.00 on account of the position of the "100" stop. For 3.05 depress "zero" key twice to bring the carriage to the unit column; then key 3, "zero" and 5. For .01 draw carriage one space to the right and depress key 1. The carriage is again returned to its normal 100.00 position and for the final item of the column, the stop 100 is released and the carriage drawn to the right to the 1,000.00 column indication, whereupon key 1 is depressed, or if stop 100.000.00 is set depress "zero" key twice and then key 1.

45 It is, of course, not essential in using the

machine to employ the stops 61, 62 and 63, as they are intended merely for convenience when continually adding columns of figures having a more or less uniform number of unit columns.

70 The reciprocals of numbers may be suitably marked on the recording keys and the machine used for subtraction and division. Multiplication is accomplished by holding the "zero" key depressed as the different 75 columns are being multiplied, as will be understood.

From the foregoing description, taken in connection with the accompanying drawings, the construction and operation of the 80 invention will be readily understood without requiring a more extended explanation.

Having thus described my invention, what I claim is:—

1. An adding machine comprising, in 85 combination, an axle, a plurality of number wheels, rotatably but not longitudinally movable on said axle and each having a ratchet, a pawl carried by each wheel and adapted for engagement with the ratchet of 90 the next adjacent wheel, cams fixed on said axle between said number wheels, a clearing wheel fixed on said axle adjacent one endmost number wheel and having a ratchet adapted to be engaged by the pawl of the 95 number wheel adjacent said clearing wheel, and means adjustable on the axle for turning the same and therethrough said clearing wheel and cams, to return said number wheels to zero position and cause said cams 100 to release said number wheels at zero position.

2. An adding machine comprising, in 105 combination, a longitudinally movable axle, means for rotating said axle, means normally engaging the holding means to retain a fixed condition of said shaft toothed number wheels on said axle, a transmitting shaft in fixed parallel relation with said axle and having a main toothed transmitting wheel 110 adapted to mesh with anyone of said number wheels when brought in registry therewith, and pawls for said transmitting and number wheels for maintaining the same in position to permit of lateral relative movement thereof, into and out of mesh relation.

3. An adding machine comprising in 115 combination, number wheels, a main transmitting wheel adapted for mesh engagement with anyone of said number wheels upon movement thereof relative to said transmitting wheel, a frame provided with a rack and a key stop bar, a pinion meshing with said rack and operatively connected with said transmitting wheel to rotate the same on movement of said rack in one direction, a plurality of keys, devices normally holding said keys in a starting position, and arms for said keys disposed at different distances 120 from said stop bar.

4. An adding machine comprising, in combination, a main transmitting wheel, a 5 slidable carriage with a plurality of number wheels adapted to be serially brought into mesh relation with said transmitting wheel, means for locking the carriage to maintain such mesh engagement, key mechanism for operating said transmitting wheel, and a zero key device for operating said 10 means to release said carriage.
5. An adding machine comprising, in combination, a main transmitting wheel, a locking element, a carriage, a plurality of number wheels on said carriage adapted to 15 be serially brought into mesh with said transmitting wheel, key devices for operating said transmitting wheel, means for locking said carriage and said element, and a zero key device for operating said means 20 to release engagement thereof from said element and from said carriage to permit shifting movement of the latter.
6. An adding machine comprising, in combination, a carriage, an axle journaled 25 on the carriage, a plurality of number wheels, rotatably but not longitudinally movable on said axle and each having a ratchet, a pawl carried by each wheel and adapted for engagement with the ratchet of 30 the next adjacent wheel, cams fixed on said axle between said number wheels, a clearing wheel fixed on said axle adjacent one end-most number wheel and having a ratchet wheel adapted to be engaged by the pawl of 35 the number wheel adjacent said clearing wheel, and means for locking the axle against rotation to the carriage, said means being releasable and operative for turning the axle and therethrough said clearing 40 wheel and cams to return said number wheels to zero position and cause said cams
- to release said number wheels at zero position, substantially as set forth.
7. An adding machine comprising, in combination, a carriage, an axle, a plurality 45 of number wheels rotatably but not longitudinally movable on said axle and each having a ratchet, a pawl carried by each wheel and adapted for engagement with the ratchet of the next adjacent wheel, cams 50 fixed to said axle between said wheels, said cams being timed to throw the pawls of one wheel out of engagement with the ratchet of the next adjacent wheel to release said number wheels at zero position upon rotation of said axle, and a spring projected locking device movable longitudinally of the axle to lock the axle against rotation or 55 release it to permit it to be turned, said device serving as a means whereby the axle 60 may be turned for the purpose described.
8. An adding machine including an automatically retractable rack, operating keys for transmitting varying degrees of motion to the rack, an automatically movable carriage, an adding train supported by the carriage, an axle in gear with the carriage, a transmitting gear loose on the axle, a clutch device for transmitting motion to the gear from the axle when the rack is 65 moved by the operating keys, a carriage escapement device controlled by said clutch device, and a key for controlling said clutch device to shift the escapement to carriage releasing position independently of the said 70 transmitting mechanism.

In testimony whereof I affix my signature in presence of two witnesses.

GUSTAVE M. NELL.
